G. REYNOLDS

SPRING HINGE FOR PULP SCREENS

Filed Nov. 26, 1927

UNITED STATES PATENT OFFICE.

GEORGE REYNOLDS, OF ANDERSON, INDIANA.

SPRING HINGE FOR PULP SCREENS.

Application filed November 26, 1927. Serial No. 235,863.

This invention relates to a spring hinge or resilient mounting or connection for the diaphragm in pulp machines and the like.

It is particularly aimed to provide a substantially non-breakable and adjustable construction whereby the blocks can be maintained centered with respect to the operating cams, and one having a bar holding down the outer ends of the springs to avoid breaking of the springs at the base or zones of attachment, and a more secure underarm having a particular fit with the angle iron to lessen vibration.

A very important object is to produce a construction wherein the springs will flex from lines intermediate their fastenings to avoid breakage as aforesaid.

Various additional objects and advantages will be pointed out or become apparent from a consideration of the description following taken in connection with accompanying drawings illustrating an operative embodiment.

In said drawings:

25 Figure 1 is a view in cross section taken transversely through a pulp machine having my improvements applied thereto;

30 Figure 2 is a front elevation of the parts of Figure 1;

35 Figure 3 is a plan view of the hinge device, partly broken away to disclose details; and

40 Figures 4 and 5 are sectional views taken on the lines 4—4 and 5—5 of Figure 3.

45 Referring specifically to the drawings, A generally designates a conventional paper pulp or similar machine, whose specific structure forms no part of the invention and which is illustrated to make my invention clearer.

50 The pulp box, receptacle or hopper is shown at 10 having usual diaphragms operating therein through vertically movable plungers 11 by operation of cams 12 with which they contact, and which cams are mounted on a

55 shaft 13 rotated from any suitable source of power. A reinforcing angle iron 14 extends below the box 10, joining and reinforcing the sides of the machine or frame thereof.

In carrying out my invention, a rigid under arm 14^a has a hook terminal 15 which engages the vertical flange of angle bar 14 and its other terminal is bolted at 16 to the sill of the screen.

Two return spring plates or members 17 and 18 are used for the plungers 11 and the diaphragms operated thereby. Relatively

adjustable anchor plates 19 and 20 have inter-engaging serrations 21 and the former has interengaging serrations with the angle iron 14 at 22. Bolts 23 pass through holes 60 in spring 18 and said plates 19 and 20 and the under arm 14^a. One end of spring 17 is curled into a clamp 25, which surrounds a pin 26 carried by the plate 19 and is fastened thereto by bolts 27. Said pin 26 is removable, being secured in place by screw members 28 carried by the plate 19 and having cylindrical extensions 29 on which the pin 26 will rock. The opposite end of spring 17 is free, being located in an opening 30 in the 70 plunger 11, and which opening is enlarged with respect to the said spring end. Such end is also formed into a clamp 31 which encloses a pin 32 for reinforcement of such end. The adjacent end of spring 18 has an L-shaped 75 terminal 33 so that it may fit the top and bottom walls in the slot or opening 30 and house the adjacent end of spring 18, permitting vertical movement thereof relatively.

To prevent the flexing of the spring members 17 and 18 from their connections and insure flexing intermediate such connections, a hold-down in the form of a T-shaped bolt or fulcrum member 35 is provided. Bolt 35 has a shank 36 passing through slots in 85 spring members 17 and 18 and underarm 14^a, and the slot of spring member 17 being longitudinally elongated and designated 36. Shank 36 depends from a cross arm 37 resting on spring member 18 and having depending terminal lugs 37^a at the sides of the spring member 17 and 18 to assist in holding them against relative lateral movement.

The opening or slot in plate 19 which accommodates bolt 23 and designated as 38 and 90 is enlarged to facilitate adjustment of the parts to center the machine blocks relatively to the operating cams 12.

Various changes may be resorted to within the spirit and scope of my invention.

I claim:—

1. In a machine of the class described, in combination with a plunger provided with a slot, and relatively stationary guide means for the plunger, return spring means extended into said slot, means to anchor said return spring means, an under arm, and hold-down means for said spring means secured to the under arm.

2. In a machine of the class described, in combination with a plunger provided with a slot, a return spring having an L-shaped ter-

minal disposed in said slot, a second return spring, the latter spring having one end located within said terminal, and means anchoring said springs.

5. 3. In a machine of the class described, in combination with a plunger, return spring members engaging said plunger, a relatively stationary iron, securing plates constituting terminals for said springs, means securing 10 said plates adjustably together and to said iron, an under arm secured to said iron, and hold-down means for said springs secured to the under arm.

4. In a machine of the class described, a

spring device comprising a spring member 15 having an L-shaped terminal; a spring member at one end disposed in said terminal and movable relatively thereto, engaging serrated clamp plates, a clamp on one of the spring members engaging one of the plates, 20 fastening means securing the other spring member and the plates adjustably together and adapted for connection to a support, and a hold-down for the springs passing therethrough. 25

In testimony whereof I affix my signature.

GEORGE REYNOLDS.
